DENTAL DAM FRAME

Dennis G. Brave, 1600 Garrett Road,
Upper Darby, Pa. 19082

Filed Apr. 1, 1970, Ser. No. 22,166

Term of patent 14 years

Int. Cl. D24—03

U.S. Cl. D24—1

Fig. 1.

Fig. 2.

Fig. 3.

Fig. 4.

Fig. 5.

FIG. 1 is a front elevation of a dental dam frame for retaining a thin apertured rubber sheet in the course of dental procedures;

FIG. 2 is a left end view of FIG. 1;

FIG. 3 is a top view of FIG. 1;

FIG. 4 is a vertical sectional view along line 4—4 of FIG. 1; and

FIG. 5 is a horizontal sectional view along line 5—5 of FIG. 1.

I claim:

The ornamental design for a dental dam frame, as shown.
